Primary Examiner — Eric L Goodman*Assistant Examiner* — Amy C Wierenga(74) *Attorney, Agent, or Firm* — C. Brandon Browning; Maynard, Cooper & Gale, PC(57) **CLAIM**

The ornamental design for an restrained gasket, as shown and described herein.

DESCRIPTION

FIG. 1 is a perspective view of a first side of a front of the restrained gasket.

FIG. 2 is a perspective view of a second side of the front of the restrained gasket of FIG. 1.

FIG. 3 is a perspective view of the first side of a back of the restrained gasket of FIG. 1.

FIG. 4 is a perspective view of the second side of the back of the restrained gasket of FIG. 1.

FIG. 5 is a sectional view of the restrained gasket of FIG. 1, taken along line 5-5 of FIG. 1; and,

FIG. 6 is an enlarged detail portion view taken from FIG. 5. The broken lines shown in the drawings are for the purpose of illustrating portions of the restrained gasket that form no part of the claim. The dot dash broken line indicates cutoff boundaries for the enlarged detail view that form no part of the claim.
